HAND OPERATED HYDRAULIC THRUSTING DEVICE
 Philip E. Ashton, 749 Yale Ave.,
 Meriden, Conn. 06450
 Filed Oct. 24, 1966, Ser. No. 589,002
 9 Claims. (Cl. 60—52)

The present invention relates to presses and other mechanisms having means of transmitting thrust through a ram or similar member and which are operated by a combination of mechanical and hydraulic means. An object of the invention is to provide a device in which a ram or similar member may be thrustingly moved by mechanical means until it encounters a given resistance to such movement and thereon the mode of operation changes to a hydraulic means with an accompanying change in the overall mechanical advantage of the device.

A further object is to provide a small mechanical-hydraulic thrust producing mechanism which may be operated, locked under load, or unlocked and have its ram retracted, all by movement of a single handle in a simple up and down motion.

Still another object is to provide a small thrust producing unit which may readily be mounted on, or removed from, a convenient support for use or repair.

An additional object of the invention is to provide a small mechanical-hydraulic device wherein the ram may be advanced through its whole stroke in a single movement of an operating lever with relatively low mechanical advantage or may be advanced in a plurality of steps through the same distance at a relatively high mechanical advantage by a number of movements of the operating lever.

How these and other objects of the invention may be accomplished will be apparent in the light of the following disclosure and the accompanying drawings of which:

FIG. 1 is a side elevation of a small bench press which embodies the invention;

FIG. 2 is a sectional elevation, on a somewhat larger scale, taken on the center line of the mechanism of FIG. 1;

FIG. 3 is a fragmentary sectional elevation of FIG. 2, taken on the line 3—3;

FIG. 4 is an enlarged sectional view of the upper part of the pump mechanism shown in FIG. 2, and

FIG. 5 is a fragmentary side elevation of the guide and latch structure as seen from the line 5—5 of FIG. 3.

Throughout the drawings, like numerals indicate like parts.

Referring to the figures, there will be seen a support 10 of generally conventional design. It has a working area 11 on which tools or work pieces may be carried and over this a bracket 12 to hold a thrust unit 13 comprising a ram guide 14 suitably threaded and retained by nuts 15. A ram 16 is slidably supported in the guide 14 and is coupled to an operating lever 17 as will be later explained. The thrust unit 13 is a generally cylindrical housing 18 secured to the upper end of guide 14 and serves both as a reservoir for working fluid and as a working cylinder wherein hydraulic thrust on the ram is developed. The housing 18 has a pendent forked bracket 19 on which the lever 17 is carried by fulcrum pin 20 passing through a slot 20a in the rearward end of lever 17.

Turning specifically to FIG. 2 showing the thrust unit in a vertical center-line section. The ram guide 14 has a bearing bushing 21 at each end, in which the ram 16 is actually carried, the said guide is preferably threaded at the lower end for attachment to the support 10 at the upper end for attachment to the housing 18 (though a flange joint is a suitable alternative); these threads carry the whole reaction load of any thrust transmitted through the ram 16 to work or tools (not shown) carried in sup-

2

port 10. The housing 18 is preferably of cast iron and is bored to two diameters, a larger one 88 and a smaller one 22, suitably finished to serve as a working cylinder for piston 23 which carries a conventional O ring 34 as a seal; this affords a shoulder 24 at the junction of the two diameters. The cylinder head 25 has two diameters to match those of the housing 18 and it is grooved at mid-height to carry an O ring 26 which has sealing engagement with the wall of the larger bore 88 and at the same time is in contact with the shoulder 24. A split spring retainer ring 27 seats in groove 28 which is so spaced from the shoulder 24 as to hold O ring 26 under compression against the said shoulder. This arrangement affords a rugged and inexpensive way of holding the cylinder head in place. The space above the cylinder head 25 serves as a reservoir 89 for the working fluid. A suction or check valve 29, of conventional construction allows ingress of fluid from the reservoir, through head 25, into the working cylinder but allows no flow in the reverse direction. An undercut 30 may be cast in place to facilitate finishing the bore 22 and a vent 30a may be provided to release air during operation.

A pump assembly 31 is mounted on the ram 16, concentric with it and partly inside it; the pump's barrel 32 is finished externally for sliding sealing engagement with an O ring 33 located in a recess in the cylinder head 25 and there held by the press-fitted retainer 35. The lower end of barrel 32 has a number of ports 36 and is closed by a plug 37 which may be brazed in place, the said plug is drilled for the piston rod 38 and has a counter-bore for the O ring 39 which is held in place by a press-fitted retainer 40. The ram 16 is machined out from the top to three diameters, all co-axial with the ram, the first one 41 affords an annular space 42 around the barrel 32, the second one 43 is a close supporting fit for the said barrel below the ports 36 while the third and lower diameter 44 is sized for threading as at 45 to receive mating threads on the lower end of plug 37 and, beyond the threads, it serves as a guide for the cross-head 46 of piston rod 38, which parts may be secured together by any convenient means, screw thread for instance. Referring to FIG. 4, there is within the pump barrel 32 a piston 47 which is not secured to the piston rod 38 although movable thereby, as will be later explained. The piston 47 has a central passage 48 appreciably larger than the rod 38 which passes therethrough, and is grooved for an O ring 49 having a sliding sealing fit with the interior of barrel 32, said piston 47 is made cup-shaped at the top to receive and hold an O ring 50 which has no contact with the wall of said barrel. A suitable bushing 51 is carried, by screw threaded engagement, on the piston rod 38 slightly below its upper end. Below bushing 51 a cruciform washer 52 is press-fitted on the rod 38 against a shoulder 53; as shown in FIG. 4, the piston 47 is loosely located between the said bushing and the cruciform washer; if the piston rod 38 is moved downwards, the bushing 51 engages O ring 50, sealing the passage 48 and the piston will thereafter move downward with the piston rod, but when the motion is reversed the cruciform washer 52 will engage the lower edge of piston 47 to move it upward, while the bushing 51 will be disengaged from the O ring 50 and so open the passage 48.

The pump barrel 32 has an external screw thread 54 at its upper end and secured thereby is a valve unit 55 which comprises body 56, ball valve 57, spring 58, plug 59 and gasket 60, the body 56 has a cavity 61 internally threaded to match the thread 54, the end face of the said cavity is smooth for sealing engagement with the end of the barrel 32 and has a central and preferably square hole 62 which is sized to afford sliding support to the upper unthreaded end of piston rod 38 while allowing the passage of fluid. A drilling 63, of two concentric diameters affords a shoulder 64, serving as a valve seat for valve 57, and its

larger portion is threaded to take the hollow plug 59 which serves as a carrier for spring 58; a further drilling 65 connects drilling 63 with the reservoir 89 and affords fluid access to the valve 57. The central hole 62 traverses drilling 63 to form a recess or pocket 66. If the piston rod 38 is moved upward from the position shown in FIG. 4, its tip will strike the valve 57 and move it from its seat 64; the pocket 66 makes space for this. A split spring ring 67 is located in the barrel 32 immediately below the body 56 to prevent piston 47 contacting bushing 51 while valve 57 is being unseated. It should be noted that the above described organization of piston 47 and associated parts constitutes a valve which is positively opened and closed by the relative movement of O ring 50 and bushing 51. Such a valve may also open under suction but the use of check valve 29 to admit fluid to cylinder 22 is preferred, as if there is too much friction between O ring 49 and the barrel 32, suction may fail to overcome it.

Returning to FIG. 2, a guide sleeve 68 surrounds and is slidable on ram-guide 14. In turn, it is surrounded by the mid-portion of lever 17 which here forms an encircling yoke 69. As shown in FIG. 3, a wrist-pin 70 passes from side to side through said yoke and sleeve 68 and also through ram-guide 14, ram 16 and cross-head 46. Wrist pin 70 may be secured by conventional means or force fit into the yoke. Slots 71 and 72, of similar width, are cut through said ram-guide and ram respectively to accommodate said wrist-pin and allow it to move axially of them. Sleeve 68 serves to support wrist-pin 70 against movement in directions other than axially of said ram guide and said ram. Sleeve 68 has a boss 73 and, secured thereto by screws 74, is a carrier plate 75. A latch pin 76 has a head 77 which is slidingly supported in a drilling 78 that is a little smaller in diameter than the width of the slots 71 and 72, the pin's shank is similarly supported in a hole through plate 75; a compression spring 79 is carried on said shank between head 77 and plate 75 to urge them apart, their relative movement being limited by the shank being spun over as at 80. A groove 81 having divergent bevelled sides is cut in ram 16 slightly above the slots 72 which, at their upper ends, are also bevelled. A tongue 82, which may protrude into the said groove, is formed on the head 77, and is bevelled to match the walls of groove 81, the said groove is considerably wider than the thickness of said tongue. The crosshead 46 has a boss 83 encircled by a short stiff spring 84 which may be compressed between the said crosshead and the bottom of plug 37.

A cover 85 having a breather hole (not shown) serves as a lid over the fluid in the housing 18, and may conveniently be retained by its skirt 86, having a friction fit on O ring 87.

Operation

It will be seen that the mechanism described comprises four major sections; (a) the body section including housing 18 with its cylinder 22 and ram guide 14; (b) the thrusting section which includes piston 23 and ram 16; (c) the pump section comprising pump 31 and (d) the actuating section which includes lever 17, and sleeve 68 and is coupled to pump 31 by wrist pin 70 passing through cross-head 46. When the latch pin 76 engages ram 16 via its tongue 82 and a wall of groove 81, all movable parts are mechanically interlocked and may be moved in unison by manipulation of lever 17. When the tongue 82 is in groove 72, manipulation of the lever 17 may occasion hydraulic operation by reciprocation of crosshead 46, piston rod 38, and piston 47, relative to pump barrel 32, but it will not afford direct mechanical movement of ram 16.

Assuming the parts to be in the position shown in the drawings and with no obstacle beneath the ram 16; downward movement of lever 17 will carry ram 16, piston 23 and pump 31 together in the same direction. During such motion fluid will be drawn from the reservoir 89, through check valve 29 and into cylinder 22 above piston 23, this movement may be continued for the full stroke of the thrusting section. If, however, the ram meets an obstacle

offering sufficient resistance, the bevel (angular) engagement of tongue 82 with the lower wall of groove 81 will force latch pin 76 back against the bias of spring 79 and allow guide sleeve 68, inner crosshead 46 and piston rod 38 with piston 47 and bushing 51 to move downwardly of pump barrel 32. During this motion, tongue 82 will first ride on the ram wall above slot 72 and then drop into the said slot to allow free operation of the parts involved. Continued downward movement of the actuating section will, because bushing 51 has contacted O ring 49 and so closed passage 48, force fluid through ports 36 into annulus 42 and on into the working cylinder 22 to apply hydraulic pressure on to the piston 23 and ram 16; at the same time more fluid will be drawn past valve 57 into barrel 32. If the motion of lever 17 is now reversed, piston rod 38 will move bushing 51 upward away from O ring 49 allowing cruciform washer 52 to engage the lower edge of piston 47 and carry it upward, with passage 48 open, and fluid in the barrel 32 will pass beneath piston 47 and become available for displacement into cylinder 22. If lever 17 is further reciprocated, the pumping action will continue to move the thrusting section downward, tongue 82 being in slot 72 throughout the whole cycle. By virtue of the valve action above described, the ram may be left locked under hydraulic load for as long as desired.

To release the ram and move it upward, lever 17 is moved upward to cause tongue 82 to ride over the bevelled end of slot 72 and pass on into groove 81 and partly across it, at which time the tip of piston rod 38 will strike valve 57 and move it sideways from its seat, during this train of events passage 48 will be held open by piston 47 striking ring 67 so that it cannot be carried, by the flow of fluid passing through passage 48, into contact with bushing 51. The movement of piston rod 38 while unseating valve 57, is accompanied by the compression of spring 84 which affords a distinct "feel" and obviates accidental release of pressure. After pressure has been released, contact of crosshead boss 83 with the lower face of plug 37 will cause the ram to rise without the valve 57 being squeezed by the piston rod 38.

The parts should be so proportioned that upward travel of lever 17 is limited by contact between the upper surface of sleeve 68 and housing 18 so as to avoid undue pressure on the bottom face of plug 37 or other internal parts.

The foregoing description concerns an embodiment of the invention in a small press that may be left locked, under load, and may also be pumped through any portion of its stroke. A simplified version is also practical for many uses (rivet heading, staking and marking for example) wherein the whole valve unit, 55, may be omitted. Such a press would then, as before, operate hydraulically at any point of its stroke, but only for the relatively short distance afforded by a single stroke of pump 31 nor could it be locked under load. For example, a press having a working cylinder of $1\frac{1}{16}$ " bore and a pump cylinder of $\frac{1}{16}$ " bore by $1\frac{1}{4}$ " stroke would afford a high pressure (hydraulic) stroke of approximately $\frac{5}{32}$ ", which is adequate for many purposes.

A noteworthy feature of the construction disclosed is the ease with which it may be serviced. After emptying out the working fluid the whole internal mechanism with its seals, valves, etc. (i.e. cylinder head 25, ram 16, piston 23, pump 31 and associated O ring seals) can be withdrawn as a unit upon removing split ring 27 and wrist pin 70 and then loosening screws 74 to allow latch pin 76 to clear the ram 16; thereafter the internal mechanism may be replaced and secured by reversing the disassembly process. This permits simple unit exchange and subsequent part repair at convenience.

It will thus be seen that the objects set forth above and those made apparent from the preceding description, are efficiently attained, and since certain changes may be made in the above constructions without departing from the scope of the invention, it is intended that all matter contained in the above description or shown in the accom-

panying drawing shall be interpreted as illustrative and not in a limiting sense.

I claim:

1. A hydraulic device comprising a movable ram for operating upon a workpiece, a fluid reservoir, pump means for feeding fluid under pressure from said reservoir to said ram, said pump means being carried by and movable with said ram, and actuating means for moving said ram into engagement with a workpiece and for thereafter actuating said pump means to supply said fluid under pressure to said ram.

2. The apparatus according to claim 1 wherein said device comprises a body having the reservoir for said fluid located therein and a working cylinder with a head, the ram having one end located within said body and having attached thereto a piston cooperating with said cylinder.

3. A device according to claim 1 having a body section comprising said reservoir and a pressurizable working cylinder having a cylinder head, a piston in said cylinder attached to said ram and movable therewith by fluid pressure, said actuating means being supported at least in part by said body section and having a connecting member movable relative to said ram for actuating said pump, said actuating means including means engageable with said arm to move the same without relative movement of said connecting member.

4. A device according to claim 3 wherein said body section is a relatively rigid structure comprising a guide for said ram and a housing having a chamber constituting the reservoir and the cylinder, the cylinder head being secured within the chamber and serving as a partition between the reservoir and the cylinder, the said pump having a pump piston and extending axially of the ram adjacent the first mentioned piston and the connecting member being within a cavity in said ram, the ram and ram guide having axially extending openings affording access into said cavity for connecting means to operably connect said actuating means with said connecting member, means for engaging with said ram comprising a coupling and decoupling member extending from the actuating means through the said openings to the ram whereby said actuating means may be coupled with and decoupled from the ram, the ram, the pump, the pump piston and the actuating means being thereby movable together in unison and whereby said actuating means may affect the movement of said pump piston without directly affecting movement of said ram when said means for engaging with said rams decouples said ram and said actuating means.

5. A device according to claim 3 wherein said pump comprises a valve and a portion movable between limits to cause said pump to supply fluid under pressure to said cylinder and wherein said portion is movable beyond one of said limits to open said valve and permit the flow of fluid from said cylinder and thereby release fluid pressure therefrom.

6. A device according to claim 4 wherein the movement of the connecting member is a reciprocating movement, and the pump comprises a barrel located at least partly within the cylinder and having a part in fluid conducting communication with the reservoir, the barrel hav-

ing a closure at one end, a rod assembly attached to said pump piston and passing with sliding sealing engagement through said closure and extending there beyond into the cavity and being connected to said connecting member, said pump piston and said rod assembly constituting a delivery valve in the pump adapted on reciprocation by movement of the connecting member to draw fluid from the reservoir through said part in communication therewith and to deliver fluid inside said cylinder.

10 7. A device according to claim 4 wherein said cylinder head, said piston, said ram and said pump are secured as to be removable as a single assembly from said body section after releasing said cylinder head for withdrawal from said chamber and disengaging said coupling and decoupling means and said actuating means from said ram.

20 8. A hydraulic device of the class described, comprising a movable ram for operating on a workpiece, a body having located therein a reservoir for fluid, and a working cylinder with a cylinder head having an aperture formed therein, a piston located in said working cylinder and secured to said ram, a pump carried by and movable with said ram, for supplying fluid from said reservoir under pressure to said cylinder to operate said piston, said pump comprising a cylinder barrel coaxial with said ram located partly within said working cylinder and passing via said aperture in said cylinder head partly into said reservoir, sealing means for sealing the wall of said aperture and said barrel, said ram having a central cavity extending axially thereof away from said pump, means for actuating said pump located outside of said body and pivotably connected thereto, said actuating means including a guide slidable upon a portion of said body and having connecting means extending into said ram cavity 30 for actuating said pump and including coupling means for selectively engaging said ram for movement prior to actuation of said pump.

35 9. A device according to claim 8 wherein the means for operating said pump comprises a crosshead, said connecting means from said actuating means being connected to said crosshead, a piston rod extending from said crosshead and having a piston at the end thereof operatively located within the pump, said rod having an extension and said pump comprising an intake valve 40 openable against fluid pressure by said piston rod extension, sealing mean surrounding said rod for sealing said rod within the pump barrel and compression spring means between said sealing means and said crosshead for biasing said rod away from said intake valve whereby said actuating means is required to overcome the bias of said spring in order to move said rod beyond its normal operative stroke and open said intake valve.
